(57) **CLAIM**

The ornamental design for a rack mountable computer blade front panel assembly, as shown and described.

DESCRIPTION

FIG. 1 is a perspective view of a rack mountable computer blade front panel assembly, illustrating the top, left and front sides thereof, wherein two different sized media packages are shown in broken lines supported within the rack mountable computer blade front panel assembly for illustrative purposes only and form no part of the claimed design;

FIG. 2 is a perspective view of the top, right and front sides of the rack mountable computer blade front panel assembly of FIG. 1;

FIG. 3 is an elevational view of the front side of the rack mountable computer blade front panel assembly of FIG. 1;

FIG. 4 is an elevational view of the rear side of the rack mountable computer blade front panel assembly of FIG. 1;

FIG. 5 is an elevational view of the left side of the rack mountable computer blade front panel assembly of FIG. 1;

FIG. 6 is an elevational view of the right side of the rack mountable computer blade front panel assembly of FIG. 1;

FIG. 7 is a plan view of the top of the rack mountable computer blade front panel assembly of FIG. 1; and,

FIG. 8 is a plan view of the bottom side of the rack mountable computer blade front panel assembly of FIG. 1.
